UNITED STATES PATENT OFFICE.

WILLIAM H. MAGEE, OF WHEELING, WEST VIRGINIA.

DESIGN FOR A GLASS DISH.

Application filed January 30, 1922. Serial No. 436. Term of patent 3½ years.

To all whom it may concern:

Be it known that I, WILLIAM H. MAGEE, a citizen of the United States of America, and resident of Wheeling, county of Ohio, and State of West Virginia, have invented a new, original, and ornamental Design for a Glass Dish, of which the following is a specification, reference being had to the accompanying drawings, in which—

The figure is a side elevation of a glass dish, showing my new design.

I claim:

The ornamental design for a glass dish, as shown.

In testimony whereof, I have hereunto affixed my signature this 12th day of January, 1922.

WILLIAM H. MAGEE.
